UNITED STATES PATENT OFFICE.

JOHN F. O'CONNOR, OF CHICAGO, ILLINOIS, ASSIGNOR TO WILLIAM H. MINER, OF CHAZY, NEW YORK.

CAR HAND BRAKE.

Application filed March 1, 1919. Serial No. 279,943.

To all whom it may concern:

Be it known that I, JOHN F. O'CONNOR, a citizen of the United States, residing at Chicago, in the county of Cook and State 5 of Illinois, have invented a certain new and useful Improvement in Car Hand Brakes, of which the following is a full, clear, concise, and exact description, reference being had to the accompanying drawings, forming 10 a part of this specification.

This invention relates to improvements in car hand brakes.

In present practice, the most common 15 form of hand brake employed on railway freight cars is that of the vertical staff type having a hand wheel at the top thereof. The vertical staff extends alongside the end wall of the car and a platform or step is usually provided on the wall of the car so that the 20 brakeman may stand thereon and operate the foot-controlled ratchet during the setting or release of the brake.

In recent years, many attempts have been 25 made to provide increased leverage ratio for the application of the brakes by hand and many of these attempts have involved a drop-handle lever and ratchet arrangement. While the desired increased leverage ratio 30 is obtained with such devices, considerable objection has been encountered in certain quarters to the use of such devices on the ground that the brakemen, being accustomed to the ordinary hand wheel, find considerable 35 difficulty in adapting themselves to the drop-handle lever ratchet type and object to the use of the latter.

The object of my invention is to provide 40 an exceedingly simple arrangement for hand brakes for railway cars wherein the brakeman applies the brakes in the usual well known manner but is provided with a higher leverage ratio mechanism for so doing.

Another object of the invention is to provide 45 a multiplying leverage ratio arrangement for hand brakes of the vertical staff type in which the arrangement is simple, inexpensive and such that it can be applied to the usual arrangement of ordinary vertical staff now in service, with only slight 50 changes.

In the drawing forming a part of this specification Figure 1 is an elevational view of a portion of the end of a freight car

showing my improvements in connection therewith. Fig. 2 is a horizontal, sectional view upon an enlarged scale taken substantially on the line 2—2 of Fig. 1. And Fig. 3 is a vertical, detail, sectional view taken substantially on the line 3—3 of Fig. 2.

In said drawing, 10 denotes the end wall 60 of what is commonly termed a "gondola" freight car, said wall being provided with the usual small platform or step 11 on which the brakeman stands while applying the brake in the usual manner. At the bottom 65 of the car is the usual stirrup 12 forming a lower bearing for the vertical brake staff and in which is accommodated the usual spool or chain-winding drum 13.

In the construction shown, the vertical 70 staff is formed with an upper section A and a lower section B. The lower section B is journaled at its lower end as indicated at 14 in the stirrup 12 and has a squared or other non-circular section to fit 75 within the correspondingly shaped recess of the drum 13 so that the latter rotates in unison with said section B, as will be understood. The upper section A of the staff is provided at its top end with a hand wheel 80 15 of the usual form, said section A being journaled in a suitable stirrup or bracket 16 and prevented from accidental upward movement by a suitable collar or other device indicated at 17.

As clearly shown in Fig. 3, the lower end 85 of the upper section A of the staff is squared as indicated at 18 and the upper end of the lower section of the staff B is similarly squared as indicated at 19, the said adjacent 90 squared ends of the two sections of the staff being located slightly below the platform 11, as shown in Fig. 3. On the squared section 18 of the upper section A of the staff is placed a casting C having an upper ratchet 95 wheel 20, intermediate bearing section 21 and lower gear wheel 22. Said casting C extends through a corresponding perforation 23 in the platform, thus forming a suitable bearing for the lower end of the staff section A. The ratchet wheel 20 cooperates with a foot-operable pawl or dog 24 pivotally mounted on a suitable pin 25 that extends through the platform and down through a stirrup plate 26 bolted or otherwise 100 suitably rigidly secured to the under 105

side of the platform 11. The pin 25 is held against accidental removal by any suitable means such as the cotter 27.

Rotatably mounted on the pin 25 is a double gear casting D having an upper relatively large diameter gear wheel 28 and a lower relatively small diameter gear wheel 29. As shown in the drawing, the upper gear wheel 28 meshes with the small diameter gear wheel 22 on the staff section A so that rotation of the staff section A is communicated to the gear wheel 28 and from the latter to the gear wheel 29. The latter meshes with a gear wheel 30 of larger diameter, which gear wheel 30 is carried by the squared section 19 on the upper end of the staff element B. The latter is suitably journaled at its upper end in a recess 31 formed in the stirrup plate 26.

From the preceding description taken in connection with the drawing, it is evident that the leverage ratio between the staff section A and the staff section B is multiplied by an interposed gearing involving the gear wheels 22, 28, 29 and 30. It will also be observed that the brake staff is locked against accidental reverse rotation in the usual manner, that is, by the ordinary foot-controlled locking pawl and ratchet located on the usual brakeman's platform. Furthermore, the arrangement is such that the old single-piece vertical brake staff may be reemployed by taking the same and cutting it off into sections of the required length and then reforging the cut ends so as to provide the necessary squared sections to receive the corresponding gear wheels. This effects a large saving to the railroads since the only additional cost in providing the multiplied leverage ratio resides in the provision of the three gear castings, the stirrup plate 26 and a very small amount of labor required to apply the parts. The arrangement is exceedingly simple; inexpensive; and is one which is unobjectionable to brakemen accustomed to the operation of the ordinary vertical staff type of hand brakes.

Although I have herein shown and described what I now consider the preferred manner of carrying out my invention, the same is merely illustrative and I contemplate

such changes and modifications that come within the scope of the claims appended hereto.

I claim:

1. In a brake for freight cars having a brakeman's platform provided on one wall thereof; the combination with upper and lower brake staff sections having their adjacent ends disposed near the level of said platform, one of said sections being manually operable and the other adapted to have the brake chain wound therearound; of a one-piece sleeve carried by and rotatable in unison with said upper staff section, said sleeve comprising an upper ratchet wheel portion immediately adjacent the top of said platform, a lower relatively small diameter gear portion, and an intermediate bearing portion journaled in said platform; a foot-operated pawl carried by the platform and cooperable with said ratchet wheel; a larger diameter gear carried by the upper end of the lower staff section, and rotatable in unison therewith; and multiplying gearing interposed between said gears.

2. In a brake for freight cars having a brakeman's platform provided on one wall thereof, the combination with upper and lower brake staff sections having their adjacent ends disposed near the level of said platform, one of said sections being manually operable and the other adapted to have the brake chain wound thereon; of a one-piece sleeve carried by and rotatable in unison with said upper staff section and journaled in the platform, said sleeve comprising a ratchet wheel, a gear of small diameter and an intermediate bearing portion of a diameter at least equal to the outer diameter of the gear and smaller than the diameter of the ratchet wheel, a foot operated pawl carried by the platform and cooperable with said ratchet wheel; a larger diameter gear fixed on the upper end of the lower staff section and rotatable in unison therewith; and multiplying gearing interposed between said gears.

In witness that I claim the foregoing I have hereunto subscribed my name this 9th day of Feb., 1919.

JOHN F. O'CONNOR.
